UNITED STATES PATENT OFFICE

JEAN W. BICKS, OF EVANSTON, ILLINOIS, ASSIGNOR TO F. A. BLICHERT MANUFACTURING COMPANY, OF CHICAGO, ILLINOIS, A CORPORATION

DESIGN FOR A BOTTLE

Application filed November 6, 1931. Serial No. 41,636. Term of patent 7 years.

To all whom it may concern:

Be it known that I, JEAN W. BICKS, a citizen of the United States, residing at Evanston, in the State of Illinois, have invented a new, original, and ornamental Design for Bottles, of which the following is a specification, reference being had to the accompanying drawings, forming part thereof.

In the drawings Figure 1 shows a side elevation of the bottle, and Figure 2 an end elevation thereof.

I claim:

The ornamental design for a bottle, as shown.

JEAN W. BICKS.
